UNITED STATES PATENT OFFICE

FRED A. SCHMITZ AND JOSEPH STURM, OF CANTON, OHIO, ASSIGNEES, BY MESNE ASSIGNMENTS, TO THE BERGER MANUFACTURING COMPANY, OF CANTON, OHIO, A CORPORATION OF NEW JERSEY

LOCKER LATCH

Application filed August 25, 1927. Serial No. 215,422.

This invention has for its object the provision of a latching mechanism for a locker or other enclosure, which will be simple in operation, sturdy in construction, permit of easy assembly, and present withal a neat and attractive appearance.

Another object of the invention is to provide a locker door having a tubular formation at the edge thereof, which formation functions not only to reinforce the locker door, but at the same time serves as a housing for parts of the latching mechanism.

These and other objects will become more readily apparent in the course of the following description of one embodiment of the invention, taken in connection with the accompanying drawings, wherein,

Fig. 1 is a front elevation of a locker in which is embodied the novel latching mechanism;

Fig. 2 is a cross-section through the door and adjacent portions of the locker, taken on the line 2—2 of Fig. 1;

Fig. 3 is a cross-section through a portion of the tubular housing and the latching bar therein, taken on the line 3—3 of Fig. 2;

Fig. 4 is a detail view of a portion of the latching bar showing one of the hooks secured thereto, and a portion of the jamb plate showing one of the slots adapted to cooperate with the hook;

Fig. 5 is an exploded view of the handle and a portion of the housing which is adapted to receive tenoned portions of the handle.

Referring more particularly to the drawings, the locker comprises a sheet metal body 1, and a door 2 hinged thereon. The door 2 is formed at one of its side edges with a tubular reinforcement or housing 3, closed at the top by a door flange and open at the bottom to facilitate insertion and removal of the latching bar, to be presently described. The door flange and opening at the bottom of the housing are clearly shown in copending application, Serial No. 209,811, filed August 1, 1927. The housing 3 has vertically disposed slots 4 at the rear thereof, and vertically disposed slots 5 at the front thereof. The slots 4 serve a purpose

to be presently stated, while the slots 5 serve to receive parts of the handle.

The handle is formed by bending a strip 6 to a U-shape and providing tenons 7 at the ends thereof. These tenons are forced into mortised portions of a flat strip 8, as shown in Figs. 3 and 5, and are adapted to enter the slots 5 in the housing after the latching bar has been placed in the housing.

The locker body 1 is also provided with a vertically extending jamb plate 9, substantially U-shaped in cross-section, and having a laterally disposed flange or jamb strip 10, formed integrally therewith. The jamb strip 10 is preferably formed as shown, by bending or doubling the material of which the jamb plate is made, and has vertically disposed slots 11 therein at spaced intervals.

The latching bar comprises a channel bar 12, having hook saddles 13 secured thereto at spaced intervals as by spot welding. The saddles 13 are formed from short lengths of angle, and as shown in Fig. 4, an intermediate portion of one leg of the angle is bent into parallelism with the other leg of the angle to provide a bearing for a rivet 14, on which is pivotally mounted, a hook 15. In the preferred form of the invention, three such hooks are provided, one adjacent the locker handle, and the other two adjacent the top and bottom portions of the housing.

The hook 15 is formed with an inwardly sloping lower edge 16, a heel 17, and a shoulder 18, adapted to abut the lower end of a spring 19, which is secured to the web of the channel bar 12. The spring 19 normally causes the hooks 15 to occupy the position shown in Figs. 3 and 5, further downward movement of the hooks being prevented by virtue of the fact that the heel 17 of the hook is, in this position, in contact with one leg of the saddle 13. The hooks are so pivoted on the saddles, that they may be pushed upward to occupy a vertical position, substantially free of the influence of the springs 19, and this feature is of importance in that it facilitates the insertion

of the channel bar and hooks into the housing.

100

ing 3. The web of the channel bar 12 has also formed therein slots 20.

The various parts described are assembled as follows:

5 The channel bar is inserted through the opening at the lower end of the housing 3, and is pushed up into the housing until the hooks 15 thereon are opposite the slots 4, the hooks being then caused to project 10 through the slots, to occupy the position shown in Fig. 3. The handle is then mounted on the door in the following manner: The index finger of one hand is inserted through the opening at the bottom of the 15 housing 3, until it contacts with the lower end of the channel bar 12. The bar is then pushed upwardly until the slots 20 therein register with the slots 5 in the housing. The handle is then moved forward by the other 20 hand in the direction indicated by the arrows in Fig. 5, whereupon the tenons 7 will enter the slots 5 and slots 20, and the flat strip 8 of the handle will contact the housing. The finger of the hand is then removed 25 from the opening at the bottom of the housing and the channel bar 12 will fall and secure the handle against outward movement, as clearly shown in Fig. 3.

In order to prevent any relative movement between the handle and the channel bar, so as to avoid accidental displacement of the handle from the door, the web of the channel bar has secured thereto, as by spot welding, a flat spring 21, which abuts the 35 lower end of the upper tenon 7 of the handle, after the channel bar has fallen to engage both tenons of the handle.

The operation of the latching mechanism is briefly as follows:

40 When the door is closed, the sloping edges 16 of the hooks ride up over the lower edges of the slots 11 in the jamb strip 10, and when these sloping edges have passed entirely through the slots, the hooks are 45 forced downward into the latching position shown in Fig. 3, by means of the springs 19. The door may then be opened by moving the channel bar 12 upwardly by means of the handle 6, until the hooks are clear of 50 engagement with the jamb strip 10.

It should be noted that the force or effort required to close the door of the present locker is considerably less than that required to close the door of a locker wherein 55 the latching is effected by complete upward movement of a relatively heavy latching bar. Moreover, the latching bar of the present invention may be inserted into the housing without the necessity of forming 60 the housing around the bar.

Having described our invention, what we claim is:

1. In combination with a locker comprising a body having a hinged door and a tubular reinforcement extending along one 65

edge of the door and arranged to form a housing; latching mechanism disposed in said housing and comprising a bar having hooks pivotally mounted thereon, and springs normally urging said hooks into their lowermost pivotal position. 70

2. Latching mechanism for a locker comprising a bar having hooks pivotally mounted thereon and spring secured to said bar adjacent said hooks, said springs normally urging said hooks into their lowermost pivotal position. 75

3. Latching mechanism for a locker comprising a bar, hook saddles secured to said bar at spaced intervals thereon, hooks pivotally mounted on said saddles, and springs secured to said bar adjacent said hooks, and acting to normally urge the hooks into their lowermost pivotal position. 80

4. Latching mechanism for a locker comprising a bar of channel cross-section, hook saddles secured to the web and one flange of the bar at spaced intervals thereon, and hooks pivotally mounted on said saddles and disposed parallel to the flanges of the 85 bar. 90

5. Latching mechanism for a locker comprising a bar of channel cross-section, hook saddles secured to the web and one flange of the bar at spaced intervals thereon, hooks 95 pivotally mounted on said saddles and disposed parallel to the flanges of the bar, and springs secured to the web of the bar above the hook saddles, and acting to normally urge the hooks into their lowermost pivotal 100 position. 100

6. In combination with a locker door having a tubular reinforcement at one edge thereof, arranged to form a housing; latching mechanism disposed in said housing and 105 comprising a bar having hooks pivotally mounted thereon, and springs normally urging said hooks into their lowermost pivotal position. 115

7. In combination with a locker door having a tubular reinforcement at one edge thereof, arranged to form a housing; a latching bar having hooks pivotally mounted thereon and insertable endwise into said tubular reinforcement. 110

8. In combination with a locker door having a tubular reinforcement at one edge thereof, arranged to form a housing; a latching bar having hooks pivotally and resiliently mounted thereon and insertable 120 endwise into said tubular reinforcement.

In testimony whereof we affix our signatures.

FRED A. SCHMITZ.
JOSEPH STURM.
